UNITED STATES PATENT OFFICE.

HERMAN SCHINDLER, OF MILWAUKEE, WISCONSIN.

SLIDE TROMBONE.

Application filed September 21, 1922. Serial No. 589,543.

This invention relates to improvements in slide trombones.

Heretofore, it has been common practice to construct slide trombones by placing the inner tubes of the mouth piece and of the pavilion end within the outer tube or slide end of the trombone and allowing considerable play between them. This practice has led to serious results in that the tubes, when in use, were continually bearing against each other and causing considerable wear which, in time, became so extensive as to require the replacement of the worn parts with resultant inconvenience and expense to the possessor of a trombone.

The old practice of constructing slide trombones, in which the inner and outer tubes were loosely fitted, caused the outer or slide tubes to wear excessively and no provision was made for relieving these tubes of excessive wear.

Slide tubes have previously been constructed by soldering tubular portions together and connecting their ends by soldering a one piece handle to them. When the open ends of the slide had become worn due to their frictional engagement with the inner tubes, it was necessary to disassemble the slide and reconstruct it by replacing the worn open end portions with new ones. It was not, under the old practice, necessary to accurately align the tubes axially for the reason that the inner diameter of the outer tube was greater than the outer diameter of the inner tube. It is, therefore, the primary object of this invention to provide for the outer and inner tubes of a trombone a split bushing, which may be easily replaced by a new bushing when it has become worn, and thereby to obviate the necessity under the old practice of substituting a new tube for one which has become worn by usage.

The tubes of the pavilion ends of trombones have not heretofore been fitted closely within the slide tubes. In fact, a close fit has been impossible because of the one piece construction of the slide end and the rigid connection of the tubes of the slide end by means of the handle if the pavilion end and the slide end were both made with unyielding end portions and were connected with close sliding fit. Minor inaccuracies in the spacing of the tubes of either element would obviously result in such binding as would make the instrument inoperative. For this reason it has heretofore been customary to

make a very loose sliding connection between the pavilion end of the instrument and the slide end thereof. The very looseness of the connection has led to excessive wear for the obvious reason that when the instrument is being played the slide will not always be moved in a perfectly straight line, and as a consequence points of contact will be established adjacent the ends of the telescopically related tubes, and the wear at such points of contacts will be excessive. It is one object of the present invention to provide a device wherein the tubes which make up the slide end of the trombone are adjustable to compensate for any variance in spacing of the corresponding tubes of the pavilion end of the instrument so that the bearing between the tubes of the pavilion end and those of the slide may be made with a very close sliding fit. It has already been suggested above that a special bushing is provided upon each of the tubes constituting the slide. It is desired that this bushing shall be made of such a length as to guide the pavilion tubes adequately while fitting closely to such tubes throughout the length of the bearing so that excessive wear will not be developed at any point. It is also desired to make the bushings in such form that lubrication can readily be provided between the bushing and the tubes closely fitted therein.

It is a further object of this invention to provide a handle for the outer or slide tube which may be easily adjusted to allow the inner and outer tubes to be axially aligned when the bushings have been put in place, and which may be easily disengaged when for any reason it may be necessary to repair any portion of the slide tube of the trombone.

It is a further object of this invention to provide a bushing and handle for the slide tube which may be easily and cheaply manufactured and which will greatly reduce the cost of repairing a trombone.

In the drawings:

Fig. 1 is a side elevation of a slide trombone showing the slide tube with a portion broken away and a portion of the pavilion end of the trombone removed.

Fig. 2 is one-half of a split bushing.

Fig. 3 is the other half of a split bushing.

Fig. 4 shows one end of the slide tube and the inner tube with a slightly modified bushing in place.

Fig. 5 is an end view of the bushing.

Like parts are identified by the same reference characters throughout the several views.

5 The pavilion end 1 of the trombone has a tubular portion 2 extending into one end 3 of the slide tube. The pavilion end 1 is connected to the mouth piece end 4 by a handle 5. The mouth piece end has a tubular portion 6 which extends into the tubular end 7 of the slide. It is understood that the tubular ends 3 and 7 of the slide are connected at their ends by a curved tube in the usual way.

10 15 As previously pointed out, it has not heretofore been necessary to accurately align the slide with the tubes of the mouth piece and pavilion ends, axially. However, in the present invention, it has been found convenient to allow the bushings 13, after they have been placed in operative position, to align themselves concentrically with the ends 3 and 7. Therefore, the ends 3 and 7 are also connected by a handle 8 which, in the 20 25 present construction, has an outer tube 9 integral with the end 3 and an inner tube 10 integral with the end 7. The outer and inner portions 9 and 10 of the handle 8 are telescopic. A screw 11 is threaded into the portion 9 and passes through the slot 12 in the portions 10 and is adapted to allow proper adjustment of distance between the ends 3 and 7 of the slide tube.

The slide tube of a trombone, as previously constructed, was not, at its ends, concentrically aligned with the inner tubes and was permitted to frictionally engage the inner tubes longitudinally, thereby causing excessive wear of the ends of the slide. In order to overcome this wear, a bushing 13 is provided which has a threaded end 14 adapted to be screwed into the end 15 of the slide tube. The bushing is made in two halves 16 and 17 which are provided with flanges 18 and 18'. The flange 18 of the portion 16 has dowel pins 19 and 20 adapted to fit into the holes 21 and 22 in the flange 18' of the portion 17. The flange 18' is knurled to facilitate screwing the bushing into the ends 50 55 60 65 15 of a slide. The bushing is adapted to fit slidably about the tubular portions 2 and 6.

It will be noted that I have shown the bushing element 16 constructed longer than bushing element 17. This bushing may correspond in size, shape, and appearance to bushing 17. The construction illustrated in Figures 1 and 3 is preferred, however, since bushing 16 is the lower bushing and by extending it I can provide any desired amount of bearing surface to keep the tubes 2 and 6 from sticking in the slide tubes 3 and 7. I illustrate different embodiments of my invention merely to indicate that the length of either bushing element or both

bushing elements upon a given tube may be varied as desired or to suit the requirements of any given installation.

It is preferred, however, that a bushing of the shape indicated in Fig. 3 be used on the 70 under side of the tubes 2 and 6 and a bushing of the shape shown in Fig. 2 be used on the upper side of the tubes 2 and 6. In constructing the bushing 16, as shown in Fig. 3, an oil retaining cup 16' is formed where- 75 in oil is retained to lubricate the tubes 2 and 6 as they slide upon their respective bushings 16. So far as I am aware no means have been heretofore provided for retaining oil for the purpose of lubricating the slid- 80 85 90 95 100 portions of a trombone.

It will, therefore, be noted that when it is desired to put a bushing in place about the tubes 2 and 6, the two portions 16 and 17 of the bushing 13 are placed about the tube and held in proper adjustment by the dowel pins 19 and 20. The bushing is then screwed into the end 15 until the flanged portion 18 is seated upon the end 15 with sufficient pressure to lock the bushing in position. If it is desired to remove the bushing, the reverse operation will be performed. It will further be noted that when the bushings have been put in operative position, the telescopically related ends 9 and 10 of the handle 8 will adjust themselves by reason of the slot 12 which allows the ends 3 and 7 of the slide to align themselves axially with the ends 2 and 6.

When it is desired to remove one of the 100 ends 3 and 7 of the slide, the bushings 13 may be taken off as described and the slide removed from the inner tubes 2 and 6. The screw 11 may then be removed to allow the ends 9 and 10 of the handle 8 to separate and thereby facilitate the removal of one of the ends of the slide for repair.

It will be noted that the outer end of the bushing element 17 is flared and a corresponding portion of the bushing element 17 110 is shaped to provide a receptacle 16' into which oil may be placed for the lubrication of the close fitting bearing between the bushing and the tubes slidable therein.

It will be understood from the foregoing 115 that the tubes have a very close sliding fit within the bushing elements threaded into the slide tubes. The bushing element will, of course, be made of such a length as to provide adequate guidance and bearing support for the tubes in order that there may be no binding between the tubes and the slide. Thus, there is no contact between tubes 2 and 6 and tubes 3 and 7 at any point. The tubes are related only through the bushings 120 125 above described. The arrangement is such that the bushings will take all of the wear.

It will, therefore, be seen that a bushing has been provided for the inner tubes and the slide tube of a trombone which at all 130

times keeps the tubes in axial alignment and which may be removed from the tubes when worn, and replaced by a new one, without necessitating replacement of portions of the 5 slide by new portions.

It will also be seen that an oil retaining cup has been provided whereby the sliding portions of the trombone may be at all times properly lubricated.

10 It will further be seen that a handle for the slide of a trombone has been provided which allows for adjustment between the tubular ends of the slide so that these ends may be axially aligned with the inner tubes 15 of a trombone. This handle also provides an easy method of disconnecting the tubular ends of the slide when for any reason it becomes necessary to remove one of the ends for repair.

20 I claim:

1. In a slide trombone provided with a slide having spaced tubular ends and inner tubes extending into said ends and having their outer walls spaced from the inner walls of 25 said ends, bushings within said ends and threadedly engaged therewith, each of said bushings comprising a pair of semicylindrical members having co-operating threaded portions, and means for retaining said 30 threaded portions in alignment.

2. In a slide trombone provided with a slide having spaced tubular ends and inner tubes extending into said ends and having their outer walls spaced from the inner walls of 35 said ends, bushings within said ends, each of said bushings comprising a relatively long semi-cylindrical member and a relatively short semi-cylindrical member, and releasable means for removably retaining said 40 members within their corresponding ends of said slide tube, whereby to provide an elongated, replacable bearing for said inner tube.

3. In a slide trombone having a slide provided with spaced ends, a handle provided 45 with means for varying the spaced relation of said ends.

4. In a slide trombone having a slide provided with spaced, substantially parallel 50 ends, an adjustable handle comprising a pair of telescopic members each secured to one of said ends, and means for securing said members together, whereby to vary the distance between said ends.

55 5. In a slide trombone having a slide provided with spaced, substantially parallel ends, a handle secured to one of said ends and having an adjustable connection with the other of said ends.

60 6. In a slide for trombones, the combination of a tubular end having cylindrical extensions angularly disposed from said end, a second tubular end having a cylindrical

tubular extension adapted to be mounted within the first mentioned extension, and 65 split bushings adapted to be positioned within the tubular ends of the slide.

7. In a slide trombone having an inner slide, the combination with a slide tube, of a relatively short semi-cylindrical bushing element, and a relatively long semi-cylindrical bushing element adapted to be positioned within the under side of said slide tube whereby said last mentioned bushing element presents a relatively long bearing surface to the inner slide of said trombone. 75

8. In a slide for trombones, the combination of spaced tubular ends having integral extensions disposed angularly from said ends of said extensions being telescopically engaged with each other, and a split bushing comprising a semicylindrical portion having a threaded end and a flange and dowel pins extending from said flange and a second semi-cylindrical portion having a threaded end and a flange provided with holes of which the walls engage said dowel pins whereby said threaded ends are held in registry with each other. 85

9. In a slide trombone, the combination 90 with a slide having spaced tubular ends, of a handle adjustable in length connecting said ends, and a bushing adapted to be screwed into one end of said slide.

10. In a slide trombone, the combination 95 with a slide having substantially parallel ends, of a handle adjustable in length connecting said ends, tubular rods extending into said ends, longitudinally split bushings seated upon the ends of said slide and disposed concentrically between said slide and said rods, and means associated with said bushings adapted to hold the ports thereof in alignment. 100

11. In a slide trombone having a slide 105 provided with spaced substantially parallel tubular ends and inner tubes extending into said ends and having their outer walls spaced from the inner walls of said ends; a bushing within each of said ends and comprising a pair of semi-cylindrical members, releasable means for removably retaining said members within said ends, and a handle secured to one of said ends and having an adjustable connection with the other of said ends, whereby to align said 115 bushings and their corresponding tubes. 110

12. In a slide trombone having a slide provided with spaced tubular ends, inner tubes each extending into one of said ends, and bushings each removably positioned between corresponding ends and tubes; a handle including adjustable members each carried by one of said ends for varying the spaced relation of said ends. 120
